RADIO RECEIVER

Emile Devienne, Fleurieu-sur-Saone, France

Application October 26, 1935. Serial No. 46,945
In France October 31, 1934

4 Claims. (Cl. 179—2.5)

The present invention relates to radio receivers and its object is to provide an arrangement for use with said receivers which improves the working thereof.

- 5 The essential feature of the arrangement according to the present invention consists in placing the ground wire of the receiver, preferably divided into a plurality of elements arranged in shunt, in the field created by the two conductors 10 which connect the receiver with the source of electricity, these conductors being advantageously arranged in such manner as to form a coil, which is movable with respect to said ground wire.
- 15 16 The effect obtained through this arrangement, which is chiefly important when the current fed to the receiver is alternating current, corresponds to an increase of the sonority and selectivity of the radio receiver, whereby the emissions 20 from stations normally received are translated more clearly and strongly, while it is possible to receive emissions from stations which could not be received otherwise.

The arrangement according to the present invention is particularly useful in the following conditions:

1. When the receiving set is but little selective;
2. In the case of a receiver of any kind whatever when said receiver is located in a place which 30 is not favorable to the reception of waves. As a matter of fact, it often occurs, at least in the case of radio receivers fed with current from an electric distribution system, that a receiver which works in a satisfactory manner in a given place and in most of the surrounding places, works in a defective manner in certain other places.

Furthermore, the arrangement according to the present invention makes it possible to weaken, in other cases, through an inverse adjustment, the emission of a station located at a short distance and which is too powerful.

According to the present invention none of the 45 elements of the receiving set is modified. Of course an arrangement according to the invention may be added in a permanent manner to the receiving set. But this arrangement may also be removable, so that, in order to improve any receiver, it suffices to replace the double conductor which connects the receiver with the source of electricity by the arrangement according to the invention.

It is very advantageous to devise the system in 50 such manner that the distance between the

ground wire and the double wire through which current is fed to the receiver may be adjustable.

In order to increase the action of this double conductor on the ground wire, this double conductor should preferably be wound so as to make 5 a certain number of turns, in order to create a sufficient field of induction in the vicinity of the ground wire.

If this winding, instead of including both of the wires through which current is fed to the receiver, includes only one of these conductors, only poor and even doubtful results are obtained. If, close to this winding, a winding is made with the ground wire, thus forming two reactive coils located in front of each other, unsatisfactory results are also obtained. 10 15

Other features of the present invention will result from the following description of specific embodiments of the invention.

Preferred embodiments of the present invention will be hereinafter described, with reference to the accompanying drawing, given merely by way of example, and in which:

Fig. 1 is a top view of the device according to the present invention, the upper wall of the box 25 that contains this device having been removed;

Fig. 2 is a corresponding side view;

Figs. 3 and 4 are perspective views of a modification in which the ground wire consists of several elements arranged in shunt. 30

The device shown in Figs. 1 and 2 shows a box or casing 1, provided, on one of its walls with a metallic wire 2, similar to those usually employed as ground wires. This wire must be bare. Its two ends are in contact with terminals 3, 3, 35 respectively. A movable plate 4 carries a screw 5 which extends through a milled knob 6 provided with inner threads in engagement with those of the screw, this knob being mounted to turn freely on the side of box 1 located opposite the wall that carries wire 2. With this arrangement, by turning knob 6, plate 4 is caused to move toward, or away from, wire 2. In order to guide the displacements of this plate 4, two flat prolonged parts 7, 7, fixed to the ends of said plate, 45 are engaged in slots 8, 8, provided in the walls of the box. One of these slots is visible in Fig. 2. The movable plate 4 is surrounded by several turns of the insulated double wire 9 through which current is fed to the receiver, these two 50 wires being located side by side against the plate. Fig. 1 shows one of these turns. The double conductor 9 enters and leaves the box at 10, 10, respectively. Knob 6 carries, in the usual manner a pointer 11, movable in front of a graduated 55

circle (not visible on the drawing) so as to measure the displacements of movable plate 4.

When making use of this device, the double conductor 9 is connected, on the one hand, with the source of electricity, and, on the other hand, with the radio receiver. Then one of the terminals 3 is connected to the ground terminal of the receiver and the other one to any structure (water pipe, etc.) leading to the ground. In order to obtain the best possible results, it is generally necessary to have wire 2 at a very small distance from the turns formed by double conductor 9, but said wire 2 should not be in contact with the insulating covering of these turns. Consequently screw 15 should fit in the inner threads of knob with very little play.

According to the modification of Figs. 3 and 4, the upper face 1^a of casing 1 carries, on its inner face (Fig. 3) located, in the vicinity of the 20 winding formed by the double conductor, instead of a single conductor 2 interposed in the ground wire, a plurality of elements or wires 2^a, 2^a, 2^a, . . . , of a non-magnetic metal, extending from the outer face of plate 1^a, through holes 12, 12, 25 12 . . . provided throughout said plate. On the outer face of this plate (Fig. 4), these wires, fixed by means of clips 13, 13, 13, . . . , of a non-magnetic metal, have their respective ends connected to a weld block 14, 14, provided at either end, said 30 blocks being in contact with terminals 15, 15. In these terminals are engaged the ends of the two portions 16, 16 of the ground wire, one of these portions being in contact with the ground terminal of the radio receiver, and the other one 35 with the ground.

It should be noted that wires 2^a must be disposed parallelly to the turns formed by the winding of the double wire through which current is fed to the receiver, and should not be at right 40 angles to said turns.

Of course, the specific device above described has been given merely by way of example. However, it is important that the winding formed by the feed wires should include both conductors 45 and not only one of them, if good results are to be obtained.

In a general manner, while I have, in the above description, disclosed what I deem to be practical and efficient embodiments of the present invention, it should be well understood that I do not 50 wish to be limited thereto as there might be

changes made in the arrangement, disposition and form of the parts, without departing from the principle of the present invention as comprehended within the scope of the appended claims.

What I claim is:

1. In a radio receiver arranged to be fed with electric current from a source of electricity, the combination of a winding formed by a double conductor connecting said receiver with said source, a ground wire for said receiver extending through the field created by said winding, and means for moving said winding and said ground wire with respect to each other, for adjustment purposes. 5

2. A device for use with a radio receiver adapted to be fed with electric current from an external source of electricity, which comprises, in combination, a double conductor forming a winding and arranged to be inserted between said source and said receiver, at least one wire element located in the field of said winding and extending in a direction parallel to the turns of said winding, and means for connecting the ends of said wire element to the ground terminal of said receiver and to the ground, respectively. 15

3. A device for use with a radio receiver adapted to be fed with electric current from an external source of electricity and including a ground wire and a double conductor for connecting said receiver with said source of electricity, which comprises, in combination, a plurality of wire elements connected together in shunt arranged to be inserted in said ground wire, and a winding formed of a double wire adapted to be inserted in series in said double conductor, disposed in close proximity of said wire elements. 20

4. A device for use with a radio receiver adapted to be fed with electric current from an external source of electricity and including a ground wire and a double conductor for connecting said receiver with said source of electricity, which comprises, in combination, a plurality of wire elements connected together in shunt, means for inserting the whole of said wire elements in series in said ground wire, a winding formed of a double wire and the turns of which are parallel to said wire elements, means for inserting said winding in series in said double conductor, and means for adjusting the relative position of said winding and said plurality of wire elements connected in shunt. 45
